Baldwin & Wright

UNITED STATES PATENT OFFICE.

JINDŘICH WALDES, OF PRAGUE, BOHEMIA.

SAFETY-PIN CARD OR PACKAGE.

1,417,589.

Specification of Letters Patent. Patented May 30, 1922.

Application filed August 21, 1919. Serial No. 318,946.

To all whom it may concern:

Be it known that I, JINDŘICH WALDES, a citizen of the Czecho-Slovak Republic, residing at Prague, in Bohemia, have invented 5 certain new and useful Improvements in Safety-Pin Cards or Packages (for which I have filed applications in Czecho-Slovakia, filed July 2, 1919, patented Apr. 20, 1920, No. 16,931; in Austria, filed June 23, 10 1920, and in Germany, filed July 9, 1919), of which the following is a specification.

This invention relates to devices for holding and displaying safety pins.

It is customary to attach safety pins to a 15 card or strip of paper by forcing the pointed members of the pins through the card or paper or through holes formed therein. This involves opening the pins and then closing them which takes considerable time, 20 and furthermore when the pins are thus mounted one side member of each pin is for the most part covered or concealed and as the other side member is free the pins will not lie evenly or flat on the card or paper, 25 and thus their arrangement often becomes distorted or irregular. Furthermore, when detaching the pins from the card or paper it is necessary to first separate the points from the guards before the pins can be withdrawn. 30 This also takes time and frequently the card or paper is torn or broken during the operation so that some pins, which it was not intended to remove, are released.

The object of my invention is to remove 35 these objections, and this I do by providing a holder for the pins which is formed with openings into which the pins, without being opened or unlocked, may be readily inserted and from which they may be easily withdrawn. 40 Preferably openings, holes or slits are so formed in the card or paper as to provide loops through which the pins are passed and which serve to hold the middle portions of the pins and other slits or openings are provided which form loops for holding the inner ends of the pins.

My improvements will be better understood by reference to the accompanying drawings, in which—

50 Figure 1 shows an elevation of a package of safety pins embodying my improvements, the cover being closed.

Figure 2 shows an elevation of the package with the cover thrown back.

55 Figure 3 shows a section on the line 3—3 of Fig. 1.

The general shape of the package is oblong and the paper is folded at *a* to form a body portion *A* and a cover *B*. The paper is also folded at *b* to provide a fold *c* which forms with the body a pocket *d* to receive 60 the inner ends of the pins which carry the coils *x*. As shown in Figs. 1 and 3 the cover overlaps the fold *c* so that when the cover is closed the pins are all concealed. 65

In the fold *c* I form a series of holes *e* and partially surrounding the holes I form a series of curved slits *f* made in such manner as to provide a series of loops *g*, one 70 for each pin.

In the body portion of the paper I provide a series of loops *h*. These are produced by forming slits *i* and semi-circular holes or openings *m*. In this way the loops are made more flexible and better adapted to receive 75 the pins while being inserted.

A holder of the kind shown may be easily made and the pins may be readily mounted therein. It is not necessary to open or unlock the pins before being inserted or 80 withdrawn.

Each pin while being mounted has its inner or coiled end inserted in an opening *m*, then passed under a loop *h* and then inserted into a slit *f* and beneath a loop *g*. 85 This operation may be quickly performed and when the pins are mounted in the manner described they may be displayed in an attractive manner and the loops *g* and *h* exert such pressure or tension on the pins 90 that they will always lie evenly on the paper and are not liable to accidentally move out of place. One or more pins may be easily withdrawn from the package without disturbing the others and without danger of breaking 95 or tearing the paper.

My improvements may be applied to holders made either of cardboard or paper and the package may be made without a cover if desired. While I preferably form the 100 holes *e* to provide loops *g* and preferably also use holes *m* instead of slits, very good results are obtained by employing slits in place of the holes *m*, but when such holes *m* are used they provide openings which 105 facilitate the entrance of the pins into the loops.

It will be observed by reference to Figure 3 that the pin is held securely near its middle portion and near its inner end. It passes 110 beneath the loop *h* and through the slit *f*. The guarded end of the pin lies flat upon the

upper portion of the body while the middle portion of the pin is held securely by the loop *h*. The inner portion of the pin is held by the loop *g* and the inner part of the fold *c*.

While I have shown the guarded ends of the pins as being arranged some distance from the loops and the coil-carrying ends of the pins some distance above the fold *b*, the pins may be inserted to a greater extent if preferred so that the guards will lie close to the loops *h* and the coil-carrying ends of the pins will extend to the lower portion of the pocket.

I claim as my invention:

1. A holder for safety pins made of flexible material folded to form a body portion and a part turned over upon the body portion to provide a pocket for the coiled ends of the pins, the body portion of the holder being slitted to form a series of loops through which the pins extend and the pocket portion being slitted to receive the coiled portions of the pins.

2. A holder for safety pins made of flexible material folded to form a cover, a body portion and a part turned over upon the body portion to provide a pocket for the coiled ends of the pins, the body portion being formed with parallel slits to provide loops between them to receive the pins, and the pocket portion being formed with curved slits to receive the ends of the pins.

3. A holder for safety pins made of flexible material folded to form a cover, a body portion and a part turned over upon the body portion to provide a pocket for the coiled ends of the pins, the body portion being formed with slits to provide a series of loops and openings above the slits to receive the pins and the pocket portion being formed with slits and with openings below the slits to provide another series of loops to receive the ends of the pins.

In testimony whereof, I have hereunto subscribed my name.

JINDŘICH WALDES.
